5 Claims. (Cl. 29—33)

This invention relates to new and improved apparatus for punching slat assemblies, and it has more particular reference to apparatus for punching the rolled-edge joints of those types of slat assemblies which have a number of narrow metal slats joined side by side in parallel relationship, each slat having each longitudinal edge rolled for hooked engagement with an oppositely-rolled edge of the slat immediately adjacent on either side to form hinged connections. Such slat assemblies are widely used for awnings, screens, doors, blinds, roller blinds, roller shutters and the like.

Slat assemblies of these types have been found generally satisfactory in their various applications, but they have the obvious disadvantage that the slats tend to slide longitudinally relative to one another unless they are fastened together, and it has therefore become customary to punch or pinch together the rolled sections forming the joint between each pair of slats—preferably near to the end of the joint—this operation tending to impair somewhat the hinging action between the slats but not to such an extent as to detract from the efficiency of the assembly for its required applications.

For this purpose, the generally-accepted method of joining the slats involves either sharply punching the adjacent rolled edges on the inner face of the assembly, such face being the one which is normally disposed inwards or downwards in use, such as by means of the machine described in my co-pending U.S. patent application Serial No. 147,621, now U.S. Patent No. 3,161,221, or pinching the rolled edges by inserting one jaw of an instrument or mandrel into the open end of the joint and then pressing the other jaw into the rolled edges beyond the first jaw, the effect in both cases being to express two tongues into the round-section space within the joint.

The apparatus of my aforementioned U.S. patent application Serial No. 147,621 is very useful for this purpose as it may be used with ease by even an unskilled operator to achieve rapid and accurate punching, the invention in that case consisting broadly in apparatus for punching rolled-edge joints of slat assemblies, including a punch-mounting frame adapted to be moved transversely across the slat assembly and having an engagement member adapted to engage contact portions of the slats; a punch mounted on the frame and adapted to occupy a punching position adjacent a slat joint when the engagement member is engaged with a contact portion of a slat, and means for actuating the punch when it is in a punching position so that the adjacent slat joint will be punched. The invention also embraced apparatus of this general type designed to operate semi-automatically in a most reliable and efficient manner.

However, securing the slats by either mechanical or manual punching has the disadvantages that the tongues or depressed portions do not hold firmly against one another to prevent relative lateral and longitudinal movement of the slats. Thus, the assembly will not necessarily be firm and stable, and difficulty may be experienced in handling and installing the assembly, while any longitudinal strains will tend to separate the slats.

To overcome these disadvantages associated with punched, rolled-edge joints, the invention of co-pending

U.S. patent application Serial No. 157,735, now abandoned, was devised to ensure that a slat assembly will have its slats maintained in the state of firmness in which they are held during punching or pinching, a greater resistance to relative longitudinal sliding being obtained, the invention also dispensing with the need for using a mandrel to support the rolled edges during punching in cases where such a mandrel was previously considered necessary. To achieve these objects, the invention of aforesaid U.S. patent application Serial No. 157,735 resides broadly in a slat joint in which a pair of oppositely-rolled longitudinal edges of adjacent slats are engaged to define a central space of substantially round cross-section, characterized by the provision in the space of a longitudinally-arranged plug of substantially constant cross-section and of non-brittle but dentable material engaged and dented by the inner tongue of two tongues of the rolled edges punched or otherwise expressed into the space from the normally-underneath face of the joint, the plug being of such nature that it is gripped between the said inner tongue and the opposite periphery of the central space and acts to maintain the two tongues in radial contact. Slat joints of this type and the plugs used therein will be hereinafter referred to as "the type described." As described in patent specification Serial No. 157,735 a very suitable form of plug is a strip of round-section plastic material, such as polyvinylchloride, preferably having a diameter slightly less than the diameter of the space within a joint.

My present invention aims to provide further improvements relating to the punching of slat assemblies, and it has for its principal object the provision of apparatus of relatively simple and inexpensive construction which may be easily used to insert plugs of the type described into the spaces between the rolled edges of the joints prior to punching of the joints to form an assembly having joints of the type described.

Another object of the invention is to employ improvements of the aforementioned character in conjunction with a machine using the principles of that disclosed in my patent application Serial No. 147,621 so that plugs (preferably of plastic or similar strip material) may be inserted into successive joints prior to the joints being punched successively by the said machine. Other objects and advantages of the invention will be hereinafter apparent.

With the foregoing and other objects in view, my invention resides broadly in apparatus for use in punching or indenting rolled-edge joints of slat assemblies, of the type in which means are provided for supporting a slat assembly so that the ends of the slats are transversely aligned whereby a punch may be moved across the joints on the normally-underneath face of the assembly on a line parallel to the aligned ends of the slats and may be actuated to punch successive joints; characterized in that there are provided stock supply means constituting a supply of plugs of the type described, and feed means adapted to be actuated to feed plugs in succession from the magazine means, the feed means being adapted to be moved successively past the ends of the joints and to be actuated at each joint to insert a plug therein prior to actuation of the punch on the respective joint. Other features of the invention will become apparent from the following description.

In order that the invention may be more readily understood and put into practical effect, reference will now be made to the accompanying drawings, wherein:

FIG. 1 is a perspective view of slat-punching apparatus in accordance with the invention, fitted to one end of an assembly-supporting table which is shown broken away, the feed-mechanism of the apparatus being shown

in two portions which are illustrated in vertically-separated relationship for the purpose of clarity;

FIGURE 1a is a fragmentary side elevational view of a detail of the feeding mechanism of FIGURE 1.

FIG. 2 is a sectional view of portion of the apparatus, taken along the line 2—2 of FIG. 1, but showing the feed-mechanism in assembled operative location, and

FIG. 3 is an end view of a pair of slats on the table, the joint therebetween having an inserted plug ready for punching to form a joint of the type described.

FIGURE 4 represents the electrical connections between the electric components used in the novel apparatus.

In the drawings, there is shown one end of a flat, rectangular table 10 mounted on legs (not shown) and supporting a slat assembly 11 of which the slat joints are to be punched or indented. The end of the table 10 which is shown is provided with slat-punching apparatus, as illustrated, while it is to be understood that the other end of the table which is not shown also has thereon slat-punching apparatus which is of identical but oppositely-arranged construction.

The slat assembly 11 is of normal rectangular shape, being made up of a series of parallel narrow metal slats 12 of arcuate cross-section, each of which has its longitudinal edges oppositely rolled, each edge of a slat 12 being engaged hingedly with an oppositely-rolled edge of an adjacent slat to form a joint 13. As shown in FIG. 3, each slat 12 has one edge 14 simply rolled in the direction of curvature of the slat, but the other edge 15 is oppositely rolled adjacent a longitudinal shoulder 16 of the slat, with the result that the joints 13 protrude on that side of the assembly 11 on which the slats 12 have their centres of curvature. This is the "inner" side of the assembly, whereas the other or "outer" side of the assembly is that which is normally arranged to face upwards in an assembled awning. As previously mentioned, the joints 13 are to be punched on their inner faces, and the assembly 11 is therefore disposed on the table 10 so that the inner side thereof faces upwards, the protruding joints 13 then also facing upwards.

At the end or transverse edge of the table 10, there is fixedly mounted an edge-mounting strip 17 lying flat along the edge of the table and extending inwards for a short distance, while a vertical edge-retaining bar 18 is secured outwardly thereof so that the end of the slat assembly 11 may lie on the strip 17 with the ends of the slats 12 retained on the table and aligned transversely thereof by the edge-retaining bar 18. Each end of the edge-mounting strip 17 extends beyond the table 10 and has secured thereto at right angles a horizontal, longitudinal and outwardly-extending supporting bar 19 (only one of which is shown in FIG. 1) having at its outer end a mounting block 20 for a transverse guide rod 21 arranged parallel to the edge-mounting strip 17 but spaced outwardly thereof and at a slightly higher level. It is to be understood that the word "longitudinal" is used herein relative to the direction of the length of the table 10 and slats 12, while "transverse" has reference to the direction at right angles to or across the table 10 and slats 12.

Mounted for sliding movement along the guide rod 21 is a punch-mounting frame, indicated generally by the numeral 22. For this purpose, there is provided a pivot sleeve 23 closely slidable along the guide rod 21 and pivotable thereabout, the sleeve 23 also passing through and welded to an upstanding longitudinal frame arm 24 which extends over the edge-mounting strip 17 but may be raised above the strip 17 and moved pivotally clear thereof outwardly of the end of the table 10 by pivoting the sleeve 23 about the guide rod 21. For this purpose, there is provided at one side of the frame arm 24, hereinafter referred to as the "front" side, a weighted block 25 adapted to hold the frame arm 24 normally over the strip 17, but the frame arm 24 may be pivoted as afore-

mentioned about the guide rod 21 by manually gripping and lifting the punch-mounted frame 22, a suitable upward control rod (not shown) being provided on the block 25 for this purpose, if so desired. At the same time, a draw-control rod 26 extends forward from the frame arm 24 and has a front hand-lever 27 whereby the frame arm 24 and punch-mounting frame 22 may be drawn backwards or forwards transversely with sliding movement of the pivot sleeve 23 along the guide rod 21.

Secured to the front face of the frame arm 24 above the strip 17 and extending rearward thereof is a mounting bracket 28 for a punch-actuating solenoid 29, the latter being supported thereon with its core 30 arranged in vertically slidable manner. The upper end of the solenoid core 30 extends freely above the housing for the coil of the solenoid 29, while the lower end 31 of the solenoid core 30 passes through an aperture in the solenoid-mounting bracket 28 and is therefore free to move reciprocally past and parallel to the main plane of the frame arm 24 directly above the edge-mounting strip 17. A bar 32 through the lower end 31 of the solenoid core 30 has at each end a light tension spring 33 extending vertically upwards and connected to a respective upper mounting hook 34 secured to a top plate of the coil housing of the punch-actuating solenoid 29. Thus, the solenoid core 30 will normally be maintained in the uppermost position shown in FIG. 1 by the action of the springs 33 except when the solenoid 29 is actuated as hereinafter described.

To the rear face of the frame arm 24 directly beneath the solenoid core 30, there is secured a punch-mounting block 35 having therethrough a vertical, round-section aperture coaxial with the solenoid core 30, this aperture slidably housing a rod-like, plunger type punch 36 having a coaxial, tapered punch-tip at its lower end for performing the required punching operations on a slat joint 13. The upper end of the punch 36 extends above the top of the punch-mounting block 35 so that its upper extremity may be struck by the descending solenoid core 30, and it has fixed to its upper end a yoke member 37.

The front end of the yoke member 37 has a vertical guide aperture slidably accommodating a vertical guide pin 38, extending upwards from the punch-mounting block 35, a compression spring (not shown) encircling the pin 38 between the yoke 37 and block 35 and acting normally to maintain the yoke 37 in uppermost position. The rear end of the yoke 37 has a vertical, screw-threadedly adjustable clearance screw 39 disposed clear of the outer side of the punch-mounting block 35 by virtue of the angular disposition of this end of the yoke 37, as illustrated in FIG. 1.

On the outer side of the punch-mounting block 35, there is a horizontal pivot pin 40 providing a pivot axis for a trip-mounting block 41 arranged parallel to the block 35 and adapted to be moved pivotally in a transverse plane. The lower section of the trip-mounting block 41 beneath the pivot pin 40 has a lengthwise bore housing a slideable trip rod 42 which extends from each end thereof, the front end of the trip rod 42 being provided with a guide and stabilising device to prevent rotation of the rod. The rear end of the trip rod 42 is spring-loaded so that it will normally be urged in a forward direction, and there is secured to the rear end of the trip rod 42 a safety-catch arm 43 which extends forwards and is guided for sliding movement with and parallel to the trip rod 42. The pivot pin 40 is disposed towards the front end of the trip-mounting block 41, the latter having a tension spring 44 connecting its front end to the block 35 so that the trip-mounting block 41 will normally be held pivotally raised at its rear end, the clearance screw 39 then engaging against and within a recess in the upper surface of the block 41, as illustrated. Since trip block 41 is held by the spring 44 in a position so that its rear end is lifted upwards whereas its front end is inclined toward the slat assembly disposed on the supporting table, the

front end of trip-rod 42 is normally lower than a joint between adjacent slats 12. Consequently, when the punch mounting frame or main frame 22 is moved along guiding rod 21, the front end of push rod 42 engages the next slat joint and moves rearwards within the bore of trip-block 41 against the action of the spring coupled with rod 42. Thus further movement of frame 22 is prevented when rod 42 is pushed into its rear end position. In this manner frame 22 can be stopped in a definite, desired position relative to the slat assembly. Further features and functions of the trip block 42 will be described later.

Near to the free inner end of the main frame arm 24, the punch-mounting block 35 is provided with a slide shoe 45 secured adjustably as to height by means of bolts in slotted holes. The slide shoe 45 has a non-abrasive lower contact surface adapted to ride across the slat joints 13 so that the latter may support the punch-mounting frame 22 during sliding movement. Directly above the edge-retaining bar 18, there is a roller 46 mounted to the front side of frame arm 24 by means of a bracket extending from arm 24 in forward direction. Roller 46 is adapted to engage upon the top surface of the bar 18 to take the weight of the frame 22 when there is no slat assembly on the table, and also adapted to ride up and along a ramp 47 at the rear end of the edge-retaining bar 18 so that the trip rod 42 will be carried across and above the rearmost edge of the slat assembly 11 without engaging same.

In addition to the aforementioned components which constitute the punching-mechanism of the apparatus, I provide a feed mechanism for inserting plastic plugs of the type described into the open ends of the joints 13 adjacent the edge-retaining bar 18, and also a hammer mechanism for preparing a preceding joint for the insertion of a plug.

The hammer mechanism includes a transverse pivot bolt 48 on the main frame arm 24 above and outwardly of the punch-mounting block 35, there being pivotable about this bolt 48 a bearing sleeve 49 having secured thereto an inwardly-extending actuating lever arm 50 and a downwardly-extending hammer arm 51. The inner end of the actuating lever arm 50 is pivotally connected to the lower end of a core 52 of a hammer-actuating solenoid 53, the core 52 being arranged for vertical movement in the same way as the punch-actuating solenoid core 30 except that the core 52 is normally lowermost under the influence of gravity and the weight of the lever arm 50, the operating direction of the core 52 being upwards as opposed to the downward operating direction of the punch-actuating solenoid core 30. The hammer-actuating solenoid 53 is also mounted on the mounting bracket 28 but inwardly thereof. The lower end of the hammer arm 51 is weighted and has a tapered hammer pin 54 directed longitudinally inwards, the pin 54 being arranged to move through an arc to a horizontal innermost position in which it enters and opens out the preceding joint when the solenoid 53 is actuated, the said preceding joint being the one immediately in front of the one to be punched, that is, the one which is engaged by the lower front end of the trip rod 42 at any time.

The feed mechanism for plastic plugs is designed for two successive movements, the first being to move a feed nozzle into the end of the joint to be punched, and the second being to feed a strip of plastic material, constituting a plug, through the nozzle and into the joint. The feed mechanism includes a lowermost chassis plate 55 pivotally connected to the guide rod 21 just in rear of the main frame arm 24, the pivot sleeve 23 having, for this purpose, a pair of spaced collars 56 between which a further sleeve 57 may pivot coaxially, this latter sleeve 57 having a pair of lower fixed vertical hinge arms 58 with a pivot pin 59 passing horizontally and transversely through apertures in their lower ends. Similar hinge arms 60 extend inwards from the pivot pin 59 and are

secured to a transverse mounting bar 61 which in turn is secured to the top of the chassis plate 55.

The inner edge of the chassis plate 55 has fixed thereto an upwardly-extending bracket 62 closely adjacent the edge-retaining bar 18, a slide shoe 63 on the bracket 62 having an outer portion 64 adapted to rest on the bar 18 to define the lowermost position of the chassis plate 55 and feed mechanism generally. The slide shoe 63 also has an inner portion 65 which extends downwards on the inner side of the edge-retaining bar 18 and is intended to rest, in operation, on the end edges of the slats 12, the shoe 63 then being slightly raised as a whole from the said lowermost position. The bracket 62 also has a locating lug 66 extending inwards and adapted to engage closely between a pair of lugs (not shown) transversely adjustable along the punch-mounting block 35, so that the transverse location of the feed mechanism relative to the punching mechanism may be fixed and suitably adjusted.

20 Directly above and parallel to the chassis plate 55 is a feed-mechanism slide plate 67 adapted to be moved inwards to move the aforementioned feed nozzle into an open end of a joint 13. For this purpose, the slide plate 67 has secured to its lower surface a grooved slide block 68 adapted to slide inwards along a longitudinal guide bar 69 which is located slidably in the groove of the block 68, the guide bar 69 being secured at its inner end to the inner bracket 62 for the slide shoe 63 and at its outer end to the mounting bar 61 by means of a mounting lug 70. In order to move the slide plate 67 relative to the chassis plate 55, there is a transverse cam bar 71 between the two plates 55 and 67 and having a plain outer edge movable along and against rollers 72 mounted on fixed vertical axles on the mounting bar 61, while the 30 inner edge of the cam bar 71 is stepped inwards at 73 towards its rear and bears against a roller 74 rotatable about a vertical axis on the outer arm 75 of a bell-crank 76. The latter has its fulcrum 77 towards the back end of the chassis plate 55, the outer arm 75 extending forwards and outwards, while the other or inner arm 40 78 extends forwards and inwards.

When the cam bar 71 is pulled forwards, its stepped portion in rear of the step 73 will engage the roller 74 of the bell-crank 76 to move the outer arm 75 pivotally inwards, the other crank arm 78 then also moving pivotally inwards so that its front end 79 will engage a lug 80 on and beneath the grooved slide block 68 to move the slide plate 67 inwards to required extent, thus moving the nozzle 81, on and protruding inwards from the inner edge of the slide plate 67, through a respective aperture 82 in the edge-retaining bar 18 and so into the relevant joint 13. As shown in FIG. 1, the edge-retaining bar 18 has along it a series of apertures 82 each registering with the end of a slat joint 13. The inner arm 78 of the bell-crank 76 is formed in part by a spring-steel strip 83 acting to urge the front end upwards against the lug 80 under normal conditions, while the bell-crank 76 is also fitted with a tension spring 84 which acts to urge it normally outwards.

60 Mounted on the main frame arm 24 at 85 is a mounting bracket 86 for a rotatable spool 87 for plastic lashing of solid round section, and the free end of the plastic strip is passed from the spool 87 through guide grommets 88 attached to the sleeve and then between parallel arcuate guide members 89 on the upper surface of the slide plate 67, and then under a normally-raised guillotine 90 before passing through the nozzle 81 which constitutes a holder for a cut length of strip material constituting a plug. The nozzle 81 is arranged longitudinally to be able to enter each slot joint 13 in a longitudinal sliding action. A feed arm 91 is pivoted about a vertical axis 92 at the rear of the slide plate 67 and has its front end directly over the plastic strip between the arcuate guide members 89, this arm 91 being adapted to turn through the arc of the guide members 89 so that a feed pawl 93

on the front end of the arm will grip the top surface of the plastic strip and feed it towards the nozzle 81 as the arm 91 swings from outer to inner positions. On the return or outward movement of the feed arm 91, the pawl 93 disengages and slides along the plastic strip, while another or outer pawl 94 fixedly mounted on the slide plate 67 engages the plastic strip and prevents return movement thereof.

Pawl 93 is designed principally as represented by FIGURE 1a. A flap 93a is pivotally mounted in the U-shaped head of feeding arm 91 by means of studs 93b protruding beyond the width of flap 93a inserted into opposite openings provided in the opposite walls of head 93. When feeding arm 91 is moved toward the rail member or edge retaining member 18 in direction of arrow M, the lower edge of flap 93a engages the strip-like material underneath thereof guided by the arcuate guide members 89. A pin 93c prevents flap 93a from assuming a strictly vertical position so that it extends at an angle relative to a line normal to the strip like material. Movement of head 93 in direction of arrow M causes flap 93a to swing in direction of arrow x whereby the gap between the lower edge of flap 93a and the surface of plate 67 receiving the strip-like material is decreased so that the strip like material is safely clamped to such an extent that it follows the movement of the feeding arm 91 towards the slat assembly.

When feeding arm 91 is released and returns to its initial position due to the action of spring 118, flap 93a is capable of swinging in a direction opposite to arrow x thereby increasing the gap between its lower edge and plate 67, so that pawl 93 is disengaged from the strip which does not follow the return movement of arm 91. Similar explanations are true for pawl 94, which principally is designed and functions in the same manner as pawl 93.

In operation, the complete apparatus may be drawn forwards from its rearmost position by the hand lever 27 so that the roller 46 engages the ramp 47 to move past the first joint, the apparatus then moving down so that the main slide shoe 45 engages the slats. The arrangement is such that the upward position of the trip-mounting block 41 under the action of the spring 44 causes the front end of the trip rod 42 to be lowermost to engage the next joint, and when the trip rod 42 is then depressed rearwards, the attached safety-catch arm 43 also moves rearwards so that the front end of the latter moves rearwards relative to a lug 95 on the slide plate 67, this lug 95 having previously been obstructed by the safety-catch arm 43 to prevent inward movement of the slide plate 67. At the rearmost position of the trip rod 42, the punch 36 is located directly over the joint, and the hammer pin 54 is located in longitudinal alignment with the next joint in front of that to be punched. Thus, only when the punching assembly is correctly located above a joint, can the slide plate 67 be moved inwards to feed a plastic plug into the joint.

The hand lever 27 has a grip-like action to pull forwards a flexible cable 96 in a cable sheath 97 which extends from the hand lever 27 to the front end of the mounting bar 61. The rear end of the cable 96 is attached to an upstanding front flange 98 of the cam bar 71 to be pulled forwards to move the slide plate 67 inwards by means of the bell-crank 76, the plate 67 moving inwards against the action of the spring 84, while the nozzle 81 enters the joint end which is in the punching position.

The upper end of the front flange 98 of the cam bar 71 has an aperture 100 through which extends the front end 101 of a transverse pull-rod 102 directly above the cam bar 71. Pull rod 102 is longitudinally slidable within opening 100 of flange 98. During the aforementioned inward movement of the slide plate 67, that is, away from the guiding rod 21 toward the edge retaining member 18, the flange 98 moves idly forwards along the pull-rod 102, so that there is a lost-motion effect on the pull-rod

during the first stage of movement of the cable 96. However, on the second stage of pulling the cable 96 and cam bar 71, the front flange 98 engages an adjustable nut 103 on the pull-rod 102 to urge the pull-rod forwards to operate the feed device for the plastic strip material. The rear end of the pull-rod 102 is connected pivotally at 104 to two inner and outer levers 105 and 106 respectively, the outer lever 106 having its outer end pivoted at 107 to the slide plate 67, while the inner lever 105 has its inner end pivoted at 108 to the feed arm 91. The inner lever 105 has its inner end disposed forwardly of the outer end so that as the pull-rod 102 is drawn forwards, the feed arm 91 will be caused to swing inwards to feed the plastic strip inwards and displace a preceding plug from the nozzle and into the slat joint.

It will be appreciated that this plug-feed motion therefore takes place subsequent to the movement of the slide plate 67 to insert the nozzle 81, so that the line of motion of the pull-rod 102 for this final insertion is inwardly of its initial position, and the pull-rod is provided with an upstanding lug 109 adapted, in the foremost position of the pull-rod, to engage a button 110 of a micro-switch 111 disposed on the rear face of the main frame arm 24 in the line of final operative motion of the pull-rod 102. The micro-switch 111 is electrically connected to both the solenoids 29 and 53 so that actuation of the switch cause the punch-actuating solenoid core 30 to move downwards to strike the punch 36, and the hammer-actuating solenoid core 52 moves upwards to cause the hammer mechanism to operate as previously described.

The punch-actuating solenoid 29 will cause the slat joint to be punched by the punch 36, and at the same time, as the punch 36 moves downwards, the attached yoke 37 and clearance screw 39 will move similarly so that the screw 39 will strike the trip-mounting block 41 and cause it to pivot about the pivot pin 40 to clear the front end of the trip rod 42 from the joint so that its forward return will move it across the top of the punched joint ready for engagement with the next joint as the apparatus is drawn further forwards. The yoke 37 also has an outwardly-extending arm 112 carrying a vertically-adjustable screw 113 adapted to strike the top of a vertically and pivotally movable blade 114 of the guillotine 90 so that the next length of plastic strip in the nozzle will be severed at the outer end of the nozzle to form a plug ready for pushing into the next joint through the nozzle on the next operation.

Also, as the guillotine blade 114 descends, a lug 115 thereon depresses a vertical spring-loaded rod 116 which passes slidably through an aperture in the slide plate 67 and pushes the inner bell-crank arm 78 downwards to clear the engagement lug 80, the slide plate 67 then being immediately withdrawn by a spring 117 to initial position. The movement of the slide plate 67 also removes the pull-rod 102 outwards from its engagement with the micro-switch 111 so that the solenoids 29 and 53 are de-energised. In consequence, all components will be returned to their initial positions, so that the hand-grip 27 may be used to draw the apparatus to the next joint, whereupon the sequence of operations is repeated. The return of the feed arm 91 to outer position is effected by a tension spring 118, as shown in FIG. 1.

It will be appreciated that the apparatus may be modified to operate in various ways. For example, there could be separate manual actuations of separate punching and insertion mechanisms at each joint, or the apparatus could be arranged by means of suitable electrical or other connections to operate automatically as it is drawn forwards by a simple knob, the lever-type hand-grip thus being dispensed with. Also, for stable mounting of the slat assembly 11 in a stretched condition, I provide suitable hooks along the rear edge of the table to engage the rearmost longitudinal flange of the rearmost slat. At the front end of the slat assembly, the guide rod

21 has a carefully-fitted but loose sleeve 119 with a catch bar 120 arranged as a hook thereon for engagement with the foremost slat or any other slat in front of the machine, a hand knob 121 enabling the bar 120 to be drawn forwards to stretch the assembly, the bar when released remaining in this position because the bore of the sleeve 119 will cause a lever-type catch action. In the particular form of apparatus shown in the drawings, there is a switch 122 on the frame arm 24 whereby the apparatus may be converted for operation in the manner described in my co-pending U.S. Patent application, Serial No. 147,621 for use in punching the slat joints only, the plastic then being removed from the nozzle and the punching solenoid 29 acting alone by engagement of the rear end of the trip rod 42 with a micro-switch 123, as the apparatus is drawn forwards by the hand grip 27 without any lever action.

FIGURE 4 illustrates the electrical connections between the electric elements 29, 53, 111, 122, and 123. Block 29a symbolizes a source for supplying the energy to energize the electromagnets 29 and 53. In the shown position of switch 122, actuation of micro-switch 111 connects magnets 29 and 53 in parallel with the source of energy 29a so, that punch 36 is operated and lever 51 is pivoted about pivot bolt 48. If switch 122 is brought into its other condition by moving the mechanically coupled contacts in direction z, magnet 53 is disconnected and magnet 29 is energized when micro-switch 123 is actuated by the rear end of push rod 42.

While apparatus as described will therefore be found very effective in achieving the objects for which the invention has been devised, it will be understood that many modifications of constructional detail and design may be made without departing from the scope and ambit of the invention, as defined in the appended claims.

What I claim is:

1. An apparatus for securing with each other individual slats of slat assemblies having narrow metal slats connected to each other in parallel relationship by rolled edge joints with open ends, comprising a supporting table having a supporting surface to receive the slat assembly, at least one rail member having an upper guiding edge mounted to one side of said table in a direction transverse to the longitudinal direction of individual slats of a slat assembly disposed on said table and protruding with said upper guiding edge beyond the supporting surface so to align and guide the ends of individual slats abutting thereagainst, said rail member having a plurality of slots extending parallel with the longitudinal direction of said rail member and adapted to be in register with the open ends of said rolled edge joints, guiding means extending substantially parallel with said rail member, a main frame slidable in a direction parallel to said rail member mounted on and pivotally about said guiding means and mounted slidably along said rail member, a stock supply means associated with said main frame for supplying strip-like material, means for enlarging the mouths of open joint ends, cutting means to sever plug sections of said strip-like material to be inserted as plugs into said open joint ends, feeding means associated with said main frame for feeding said strip-like material supplied by said stock supply means toward said open ends of said joints and subsequently to force said plug sections into said enlarged open joint ends, punching means mounted on

said frame and slidable therewith for indenting the joints between assembled slats after insertion of plug sections into said joints, means to actuate said feeding means, driving means for actuating said punching means and said 5 enlarging means, means to operate said driving means subsequent to actuation of said feeding means, a coupling member connected with said punching means for operating said cutting means when said punching means is actuated.

10 2. An apparatus as claimed in claim 1, wherein said feeding means has a feeding plate and a nozzle fixedly mounted thereto, said nozzle adapted to receive said plug sections and to register with one of said open joint ends, said cutting means fixedly mounted to said feeding plate, 15 one end of said nozzle adjacent a respective joint end and the other end thereof adjacent said cutting means, a feeding arm pivotally mounted on said feeding plate and adapted to engage said strip of material when moved toward said rail member and to disengage from said strip 20 of material when moved in opposite direction, said means to actuate said feeding means associated with said feeding plate for moving same in a direction transverse to said rail member toward a corresponding joint end and associated with said feeding arm for pivoting same 25 toward said nozzle in engagement with said strip of material after movement of said plate so as to force a plug section received in said nozzle from said nozzle into a joint to register therewith and to insert new strip material into said nozzle.

30 3. An apparatus as claimed in claim 2, wherein said guiding means has a rod extending in spaced apart relationship from said rail member and parallel thereto, said main frame pivotally mounted about said rod, a sliding shoe secured to said main frame and normally resting on 35 said slat assembly disposed on said supporting table so to support said main frame on said slat assembly during its travel therealong.

4. An apparatus according to claim 2, wherein said means to actuate said feeding means has a handle associated with said main frame for moving same along said rail member, said handle having a first and a second leg pivoted with respect to each other, a cable connected with one of said legs for moving said feeding plate and for pivoting said feeding arm by means of pivoting said 45 one leg with respect to the other leg.

5. The apparatus according to claim 2, wherein said enlarging means has a lever mounted to said main frame pivotally about an axis parallel to said rail member and a tapered hammer member associated with the free end of 50 said lever, the tapered end of said hammer adapted to register with an open joint end preceding an open joint end in a position to be provided with a plug section.
